UNITED STATES PATENT OFFICE.

MYLES STANDISH, OF OMAHA, NEBRASKA.

SPARK-PLUG.

Specification of Letters Patent. Patented Nov. 20, 1917.

1,247,345.

Application filed May 17, 1917. Serial No. 169,210.

To all whom it may concern:

Be it known that I, MYLES STANDISH, a citizen of the United States, residing at Omaha, in the county of Douglas and State 5 of Nebraska, have invented certain new and useful Improvements in Spark-Plugs, of which the following is a specification.

This invention relates to an improvement in spark plugs, and has for one of its objects to provide such a construction that the inner end of the central, insulated electrode will be prevented from becoming unduly heated, to thereby avoid preignition of the gas charges. Another object is to provide a metallic part or washer on the central electrode adapted to conduct heat and to cause heat to be communicated from the electrode to a conoidal face formed at the end of the stem of the insulating core, to cause combustion of soot and thereby avoid short circuits at the exposed end of the stem. Another object is to provide an insulating jacket within the stem of the insulating core, for the central electrode, so that the 20 spark plug will continue to be operative in instances when the stem becomes fractured or broken.

The invention also has reference to the formation of a recess disposed in the plane 30 of the conoidal face of the stem and opening on the end of said stem for containing a gasket and washer, and to the use of a sleeve for protecting one of the metals employed against the action of heat, said sleeve providing a support when the central electrode 35 is pressed outwardly of the insulating core for bracing and preventing vibration of the said electrode and for compressing the gasket.

With the foregoing objects in view and others to be mentioned hereinafter, the invention presents a novel construction, combination and arrangement of parts as described herein and claimed, and as illustrated in the accompanying drawing, where- 40 in.

Figure 1 is a view in side elevation of the spark plug. Fig. 2 is a view of the same in longitudinal section. Fig. 3 is an enlarged detail relating to Fig. 2.

Referring now to the drawing for a more particular description, the invention is illustrated in connection with a longitudinally apertured insulating core 4, a tubular, metallic housing or ground electrode of con-

ventional form for a spark plug, being indicated at 5.

On account of the high degree of speed at which motor vehicles are often driven, the central, insulated electrodes, usually 60 constructed of steel, attain a degree of heat sufficient to cause ignition of the gas charges before the gas has become compressed, and known as preignition.

In order that this objectionable feature 65 may be avoided, I provide for the insulated electrode a central, electrical conductor 6, preferably constructed of steel, and a tube 7 of copper or similar metal having a degree of heat conductivity greater than steel. 70

It will be appreciated that the use of steel will provide rigidity for this electrode and that steel will prevent warping. The copper, on account of its heat conductivity, 75 will readily conduct the heat from the inner end of the electrode and cause it to be communicated to the insulating core, and thence to the atmosphere to prevent pre-ignition of the gas charges.

The proportion of steel and copper for 80 the electrodes may be changed, as may be required to correspond with different kinds of motors. In instances where the inner end of the electrode is subjected to a degree of heat greater than ordinary, the tube of 85 copper may have a greater thickness, and preferably the tube has a length substantially equal to the length of the central steel conductor.

On account of vibration and stresses directed thereto, the stem *a* of the insulating core occasionally becomes broken and separated from the body of the core, or becomes fractured, to render the spark plug inoperative, from short circuits. In order that 95 these objectionable results may be avoided, the stem is provided with an insulating jacket 8, preferably constructed of mica, which circumscribes the copper tube; and on account of this construction, the stem, 100 if broken or fractured, will not become displaced or separated from the body of the insulating core, and the jacket 8 will prevent short circuits, in the instances mentioned.

Numerals 9 indicates a depression or recess disposed at the longitudinal axis and opening on the end of the stem *a*, said recess being circumscribed by a conoidal face 10, at 105 said terminal. The recess is adapted to con-

105

110

tain a gasket 11 and a metallic ring or washer 12, the latter operating as a heat-conducting element. It will be noted that the recess has a depth sufficient, only, to contain these two elements, this being a desirable feature so that the washer, when the parts are assembled, may be disposed substantially flush with the end of the stem, no depression being formed for a deposit of

- 5 carbon therein, and also that said washer will be disposed in close proximity to the inclined face 10 for conducting heat thereto.
- At 13 is indicated a sleeve provided with a projection 14 at its outer end, said sleeve

- 15 and its projection being constructed of non-incinerating metal and providing a support for member 12 when, by use of the screw-cap 15, pressure is applied to the gasket 11, the projection 14 preferably being secured to the central steel conductor. By use of this construction, if the stem *a* is fractured or broken, it will be pressed in a direction of the body of the insulating core, since the sleeve 13 and parts within the recess provide
- 20 25 a support for this purpose.

- During operation, member 12 will become intensely heated since it is in engagement with the copper tube, and this heat, on account of the attenuated terminal, will be conducted to the conoidal face 10 of the stem, with the result that combustion of soot thereon will be effected, and short circuits avoided. Member 12, preferably, is not threaded on the tube, and this feature facilitates assemblage of parts.

- While steel and copper have been specifically mentioned as the two metals used for the insulated electrode, it will be understood that other metals may be substituted, one to provide rigidity and to prevent warping, and the other to be, comparatively, a more ready conductor of heat, and to be protected from the ignited gases by member 13 or its equivalent.

45 I claim:

1. The herein improvement in spark plugs, comprising, in combination with an insulating core having its inner terminal provided with a conoidal face, an electrode traversing and projecting beyond the inner end of the core, and consisting of a central conductor, a tube circumscribing the central conductor, a coat of mica circumscribing the tube, said tube having a greater degree of heat conductivity than the central conductor, a metallic heat conducting element on the tube adjacent to said conoidal face, and a metallic non-calcinating sleeve provided with a projection and circumscribing that part of the tube which projects beyond the inner end of the insulating core.

2. In a spark plug the combination of an insulating core provided at its inner terminal with an annular recess and a conoidal face outwardly of said recess, an electrode trav-

ersing and projecting beyond the core, and consisting of a central conductor, a tube circumscribing and having a greater degree of heat-conductivity than the central conductor, an insulating coat in the insulating core and circumscribing a part of the tube, a heat conducting element engaging the tube and disposed in said recess, and a metallic non-calcinating sleeve provided with a projection and circumscribing that part of the tube 70 outwardly of the insulating core.

3. In a spark plug, the combination of an insulating core provided at its inner terminal with a recess and formed outwardly in the plane of said recess with a conoidal face, an electrode traversing and extending beyond the core and including a central electrical conductor, a tube circumscribing and having a greater degree of heat-conductivity than said conductor, packing in said recess abutting upon the insulating core, a heat conducting ring on the tube abutting upon the packing with its outer side disposed substantially flush with the end of the insulating core, and a metallic, non-incinerating sleeve 90 provided with a projection and circumscribing that part of the tube outwardly of the insulating core.

4. In a spark plug, an electrode, an insulating core within the electrode, said core having a stem provided with a recess opening on its end and having a conoidal face 95 encircling the recess, a second electrode traversing the recess and insulating core and provided with a projection, a gasket in said 100 recess, a metallic ring disposed on the second electrode in the plane of the conoidal face of said stem, a sleeve between the projection of the second electrode and the metallic ring, and means to press the sleeve 105 against the metallic ring for compressing the gasket.

5. In a spark plug, an electrode, an insulating core within the electrode, said core having a stem provided with a recess opening on its end and having a conoidal face 110 encircling the recess, a second electrode traversing and having an extension outwardly of the end of the insulating core, said second electrode including a steel conductor 115 and a copper tube circumscribing said conductor, a screw cap mounted on the second electrode, a gasket in said recess, a metallic ring disposed on the copper tube in the plane of the conoidal face of said stem, a 120 sleeve outwardly of the end of the insulating core on the extension of the tube to abut upon the metallic ring for pressing the gasket against a wall of the recess and for disposing said ring substantially flush with 125 the end of the stem of the insulating core when the screw cap is actuated.

6. In a spark plug, an electrode, an insulating core within the electrode, said core having a stem provided with a recess open- 130

ing on its end, a second electrode traversing the recess and insulating core and having an extension disposed outwardly of the end of the stem, said second electrode including a steel conductor and a copper tube circumscribing the steel conductor, a gasket in said recess, a metallic ring on the copper tube, a sleeve on the extension of the second electrode, said screw cap being revoluble for disposing said ring substantially flush with the end of the sleeve of the insulating core in engagement with the gasket.

7. In a spark plug, an electrode, an insulating core within the electrode, said core having a stem provided with a recess opening on its end and having a conoidal face encircling the recess, a second electrode traversing and having an extension outwardly of the end of the insulating core, 15 said second electrode consisting of a steel conductor, a copper tube circumscribing said conductor and an insulating coat in the stem of the insulating core encircling the tube, a screw cap mounted on the second electrode, 20 a gasket in said recess, a metallic ring disposed on the copper tube in the plane of the conoidal face of said stem, a sleeve outwardly of the end of the insulating core on the extension of the tube to abut upon the 25 metallic ring for pressing the gasket against a wall of the recess and disposing said ring substantially flush with the end of the stem of the insulating core when the screw cap is actuated.

8. In a spark plug, an electrode, an insulating core within the electrode, said core having a stem provided with a recess opening on its end, a second electrode traversing the recess and insulating core and having an extension disposed outwardly of the end of the stem, said second electrode consisting of a steel conductor, a copper tube circumscribing the steel conductor and an insulating jacket in the stem circumscribing the 40 tube, a gasket in said recess, a metallic ring on the copper tube, a sleeve on the extension of the second electrode, said screw cap 45

being revoluble for disposing said ring substantially flush with the end of the sleeve of the insulating core in engagement with the gasket.

9. In a spark plug the combination of an insulating core having a stem provided at its inner terminal with an annular recess, an electrode traversing and projecting beyond the stem of the core, and consisting of a central conductor, a tube circumscribing and having a greater degree of heat-conductivity than the central conductor, an insulating jacket in the stem of the insulating core 60 and circumscribing the tube, a gasket in the recess, a washer on the tube and disposed in said recess, and a metallic non-calculating sleeve provided with a projection and circumscribing that part of the tube outwardly 65 of the sleeve of the insulating core.

10. In a spark plug, an electrode, an insulating core within the electrode provided with a stem, a second electrode traversing the insulating core and having an extension 70 disposed outwardly of the end of the stem, said second electrode consisting of a steel conductor and a copper tube circumscribing the steel conductor, an insulating jacket in the stem circumscribing the tube, and a non-75 incinerating sleeve circumscribing the extension of the second electrode.

11. In a spark plug, an electrode, an insulating core within the electrode provided with a stem, a second electrode traversing 80 the insulating core and having an extension disposed outwardly of the end of the stem, said second electrode consisting of a steel conductor and a copper tube circumscribing 85 the steel conductor, and a non-incinerating sleeve circumscribing the extension of the second electrode.

In testimony whereof, I have affixed my signature in presence of two witnesses.

MYLES STANDISH.
